CLAIM

An ornamental design for a removable computer disk cartridge, as shown and described.

DESCRIPTION

FIG. 1 is a bottom perspective view of the removable computer disk cartridge, on a greatly enlarged scale; FIG. 2 is a side elevation view of the removable computer disk cartridge embodiment shown in FIG. 1;

FIG. 3 is a top plan view of the removable computer disk cartridge embodiment shown in FIG. 1;

FIG. 4 is a rear elevation view of the removable computer disk cartridge embodiment of FIG. 1;

FIG. 5 is another side elevation view of the removable computer disk cartridge embodiment of FIG. 1;

FIG. 6 is a front elevation view of the removable computer disk cartridge embodiment of FIG. 1; and,

FIG. 7 is a bottom plan view of the removable computer disk cartridge embodiment shown in FIG. 1 on an enlarged scale.
